HARRY A. DOUGLAS, OF BRONSON, MICHIGAN

ELECTRIC LAMP

Original application filed February 27, 1931, Serial No. 518,665. Divided and this application filed December 14, 1931. Serial No. 580,889.

My invention relates to electric lamps and is of particular service in connection with dash lamps for automobiles in which the lamps include an incandescent light bulb.

5 Among other objects, my invention aims to provide an improved dash lamp which is simple in construction and efficient in operation.

This application is a division of my co-pending application, Serial No. 518,665, filed February 27, 1931, entitled Circuit continuing devices.

The present invention may be understood from the illustrative embodiment thereof shown in the accompanying drawing, in which—

Figure 1 is an axial section, showing some of the parts in elevation, of a circuit continuing device embodying my invention;

20 Figure 2 is a view similar to Figure 1 but rotated ninety degrees and showing some of the parts in elevation;

Figure 3 is a sectional view taken on the line 3—3 of Figure 1;

25 Figure 4 is a sectional view taken on the line 4—4 of Figure 1;

Figure 5 is a view taken on the line 5—5 of Figure 1 and showing parts in side elevation and another part in section; and

30 Figure 6 is a rear end view taken on the line 6—6 of Figure 1.

Referring to the figures of the drawing, I have shown a circuit continuing device such as a dash lamp which may include a cylindrical metallic shell 1, having the integral lugs 2 and 3 adapted to engage and rigidly clamp the shell to a suitable support upon the dashboard such as a bracket, a portion of which is indicated at 4.

40 The shell 1 houses a metallic core 5 which is adapted to have rotative and longitudinal movement with respect to the shell as presently described. The core 5 is shown provided with a skirt portion 6 and an axially recessed portion 7, which is apertured at its inner end concentrically with the core. The skirt portion 6 is in close proximity to the surface of the bore of the shell. The core 5 is provided with a tubular portion 8 which is 45 coaxial with the core and is rigidly connected

to the core at the inner end of the recessed portion 7, for example by being crimped about the margin of the aperture in the recess of the core as at 9. The tubular portion 8 loosely mounts a thin metallic washer 10 55 which is adapted to support the tubular portion 8 in the shell but to permit rotative and longitudinal movement of the tube with respect to the shell and washer. The washer 10 is maintained in position in the shell 1 by the pressure of a coiled spring 11, which presses the washer 10 against an abutment such as the ears 12 formed with the shell 1 and bent to lap the washer 10. The coil spring 11, which bears also against the conical back of 65 the axially recessed portion 7 of the core 5, simultaneously presses the core 5 and its tubular portion 8 longitudinally of the shell 1 forwardly and in a direction tending to separate the core 5 and the washer 10, movement 70 in this direction being limited by a flange 13 at the opposite or rear end of the tubular portion 8.

The metallic washer 10 is also desirably provided with the peripheral spring fingers 75 40 which permit the washer to accommodate itself to the expansion and contraction of the shell 1 as already described.

A current carrying member is provided in the shell 1, which member is here represented by an insulated wire 14, which is passed loosely through the tubular portion 8 and as here shown has its terminus soldered in a cup-shaped metallic contact member 15, which is concentrically carried by an insulating washer 16, which, in turn is concentrically carried by the core 5. The contact member 15 is thus substantially coaxial with the shell 1. The washer 16 is revolvably held in the axially recessed portion 7 of the core 5, as 80 85 by means of fingers 17 struck from the core and turned to hook loosely over the edge of the insulating washer 16. The insulation of the wire 14 is continuous substantially up to the washer 16. So constructed and arranged, 90 the wire 14, together with the contact 15 and the washer 16, are free to rotate relatively to the core 5 and tubular portion 8, and the core 5, in turn, is free to rotate relatively 95 to the shell 1.

A contact carrying plug represented by an incandescent light bulb 18 having a base 19 has bayonet projection and bayonet channel connection with the shell 1, a snug fit of the 5 base 18 with the shell being assured by a spring tongue 20 which is struck from the body of the shell 1 and extends into the bore of the shell. The bayonet pins 21 are thus frictionally maintained in their seats 22. The 10 base 19 is provided with a contact 23 which is coaxial therewith and which in one of the alternative longitudinal positions of the core 5, engages the contact 15 to close the circuit. Such a position of the complementary contacts 15 and 23 is indicated in Figures 1 and 15 2, in which position the core 5 is being urged forwardly by the spring 11 and the contact 23 is being pressed into the cup-shaped contact 15. Such engagement of the contacts is 20 assured since the core 5 has not reached the limit of its forward movement as determined by the flange 13 on the tubular portion. The cup-shaped contact 15 provides a seat for the contact 23 which desirably tends to grip the 25 contact 23 and prevent flickering of the light due to vibration of the parts. To enhance this gripping effect, the periphery of the cup-shaped contact member 15 is desirably roughened slightly as at 24 to increase the friction 30 between it and the softer contact 23.

When it is desired to open the circuit, the core 5 may be moved longitudinally in the shell 1 away from the base 19, thus separating the contacts 15 and 23. I have provided 35 means for effecting longitudinal movement of the core 5 which means is here shown as inclusive of a handle 25. This handle may be locked to the core as by having a reduced portion 26 of the handle passed through a 40 slot 27 in the skirt 6 of the core. The slot 27 desirably terminates in a wide mouth 28 so that the handle can be removed by appropriate manipulation of the parts. The handle 25 extends outwardly from the core 5 45 through a cam slot here shown as the oblique slot 29 in the shell 1. By moving the handle in this slot the core may be rotated, and simultaneously with said rotation, either retracted or advanced in the shell to open or 50 close the circuit as desired. A seat 30 for the handle 25 in the slot 29 permits the core to be held in a retracted position and the circuit maintained open. The handle 25, having no grooved connection with the margins 55 of the slot 29, has no tendency to stick in the slot but moves freely therein. It is highly desirable that the wire 14 be not rotated by the rotation of the core 5, and by a construction such as I have herein exemplified, the 60 wire 14 with its terminal contact 15 is free to turn relatively to the core when the latter is being rotated during the opening or closing of the circuit, the wire turning freely in the tubular portion 8 and the contact member 65 15 turning freely in the recessed portion

of the core. The wire 14 as here shown is provided with a metallic armor 31 and the armor is desirably continued well into the tubular portion 8 so that friction is prevented between the tube and the insulation of the 70 wire which would tend to fray the insulation.

The circuit continuing device here shown for illustration being in the form of a dash lamp, I have shown a cowl 32 over the bulb 18 which directs the light from the bulb 18, by reason of an opening 33 in the cowl, upon an instrument board of an automobile, for example. The cowl 32 is here shown cylindrical and is arranged to slip snugly over the shell 1 and is held upon the shell by spring action 75 of the shell. In this instance, the shell 1 has its wall split longitudinally as at 34 continuing the bayonet channel 34^a and leaving a free segmental portion 35 of the shell which acts as a spring to provide a snug fit between the shell and cowl. The portion of the shell upon which the cowl seats includes a flange 36 which is bent back upon the exterior of the shell and provides an annular bearing 37 for the cowl. The bearing 37 is desirably spaced from the body of the shell. In accordance with my invention the flange 36 is continued longitudinally rearwardly of the shell as by the spring fingers 38 which, as 80 clearly shown in the drawing, are decreasingly tapered in longitudinal section and in width toward their free ends to progressively decrease their resiliency. In other words, the material of the flange 36 where it forms the bearing 37 is substantially the same thickness as the material of the body of the shell 1, but the material of the fingers 38 is progressively thinner from the point where the fingers join the bearing 37 to their free ends. 85

Thus as the cylindrical cowl is forced over the bearing 37 and the fingers 38 the flange and fingers yieldingly engage the cowl and the flange provides a split ring bearing for the cowl of substantially greater resiliency than the fingers 38. The spring fingers 38 being 90 reduced in thickness as well as in width toward their free ends offer substantially less resistance to distortion than the bearing 37 and the fingers at their free ends have substantially no greater resiliency than is necessary to maintain them in frictional engagement with the cowl. So constructed and arranged the function of the spring fingers is merely to frictionally engage the cowl to prevent jarring of the cowl off the bearing 95 and the spring fingers have substantially no tendency to force the cowl longitudinally of the shell and thus off of the shell as they would have if they were of uniform thickness with the material of the flange 36 forming the bearing 37. An internal rib 39 on the cowl desirably limits the extent of its engagement with the flange 36.

It will be understood that the circuit here shown for purposes of illustration is a so- 100

called single pole circuit in which the bulb 18 may be grounded through a metallic sheath surrounding the base 19 and the metal of the parts.

5 Obviously, the invention is not limited to the particular details of construction here shown. Furthermore, it is not indispensable that all features of the invention be employed conjointly, as they may be advantageously used in various combinations and sub-combinations.

I claim:

15 1. A dash lamp or the like embodying, in combination, a cylindrical metallic shell of resilient material split longitudinally; a flange at the forward end of said shell, said flange being turned back over the body of the shell and extending longitudinally rearwardly thereof spaced from said shell; continuations of said flange extending longitudinally rearwardly in the form of spring fingers, the material of said fingers being decreasingly tapered in longitudinal section toward their free ends to progressively decrease their resiliency; and a cylindrical cowl, said cowl telescoping over said flange and said fingers which yieldingly engage the cowl, whereby said flange provides a split ring bearing for the cowl and said fingers at their 30 free ends have substantially no greater resiliency than is necessary to maintain them in frictional engagement with the cowl.

20 2. A dash lamp or the like embodying, in combination, a cylindrical metallic shell of resilient material; a split flange at the forward end of said shell, said flange being turned back over the body of the shell and extending longitudinally rearwardly thereof spaced from said shell; continuations of said flange extending longitudinally rearwardly in the form of spring fingers, the material of said fingers being decreasingly tapered in longitudinal section toward their free ends to progressively decrease their resiliency; and a cylindrical cowl, said cowl telescoping over 35 said flange and said fingers which yieldingly engage the cowl, whereby said flange provides a split ring bearing for the cowl and said fingers at their free ends have substantially no greater resiliency than is necessary to maintain them in frictional engagement with the cowl.

40 50 In witness whereof, I hereunto suscribe my name.

55 HARRY A. DOUGLAS.
